[57] CLAIM

The ornamental design for an applique for wearing apparel, substantially as shown and described.

DESCRIPTION

FIG. 1 is a top plan view of an applique for wearing apparel showing my new design;

FIG. 2 is a partial sectional view taken along line 2—2 of FIG. 1; and

FIG. 3 is a perspective view thereof.

The broken line showing of a T-shirt in FIGS. 1-3 is for illustrative purposes only.

FIG. 1

FIG. 3
